US0D1011914S

(12) **United States Design Patent** (10) **Patent No.:** **US D1,011,914 S**
(45) **Date of Patent:** **** Jan. 23, 2024**

(54) **DISPENSER FOR ESSENTIAL OIL**

(71) Applicants: **Andrew S. Goldfarb**, New York, NY (US); **Joshua Goldfarb**, New York, NY (US); **Pepin Gelardi**, Brooklyn, NY (US); **Joseph Antonio Gonzalez**, Bronx, NY (US); **Emma Pearl Willmer-Shiles**, Brooklyn, NY (US); **Garret McGregor**, New York, NY (US)

(72) Inventors: **Andrew S. Goldfarb**, New York, NY (US); **Joshua Goldfarb**, New York, NY (US); **Pepin Gelardi**, Brooklyn, NY (US); **Joseph Antonio Gonzalez**, Bronx, NY (US); **Emma Pearl Willmer-Shiles**, Brooklyn, NY (US); **Garret McGregor**, New York, NY (US)

(73) Assignee: **TYNC, LLC**, New Rochelle, NY (US)

(**) Term: **15 Years**

(21) Appl. No.: **29/758,310**

(22) Filed: **Nov. 13, 2020**

Related U.S. Application Data

(63) Continuation-in-part of application No. 16/686,048, filed on Nov. 15, 2019, now Pat. No. 11,298,713.

(57) **CLAIM**

The ornamental design for a dispenser for essential oil, as shown and described.

DESCRIPTION

FIG. 1 is a perspective view of a dispenser for essential oil showing our new design;

FIG. 2 is a left side view of the dispenser for essential oil of FIG. 1;

FIG. 3 is a right side view of the dispenser for essential oil of FIG. 1;

FIG. 4 is a front plan view of the dispenser for essential oil of FIG. 1;

FIG. 5 is a rear plan view of the dispenser for essential oil of FIG. 1;

FIG. 6 is a top elevation view of the dispenser for essential oil of FIG. 1; and,

FIG. 7 is a bottom elevation view of the dispenser for essential oil of FIG. 1.

In the drawings, any broken lines depict unclaimed subject matter only and form no part of the claimed design.
